TELEVISION RECEIVER ANTENNA

Horace Atwood, Jr., Belleville, N. J., assignor to
Allen B. Du Mont Laboratories, Inc., Passaic,
N. J., a corporation of Delaware

Application February 10, 1945, Serial No. 577,291

3 Claims. (Cl. 250—33)

1

This invention relates to an antenna for a television receiver that is particularly suitable for homes. In carrying out the invention an antenna is provided which is light and convenient to handle and can be supported in a number of ways, such as by cords or the like, or upon solid supports.

With this invention a cheap and efficient television antenna can be easily produced that is suitable to be installed, for example, in the attic in a home.

In carrying out the invention two cones of conducting material are provided, each cone being approximately one-fourth as long as the wave length that is to be received and having the diameter of its large end approximately one-eighth as much as said wave length. Each cone is made of light weight insulating material coated on one or both sides with thin conducting material connected to a ring or collar at the small end thereof.

The invention may be understood from the description in connection with the accompanying drawing, in which:

Fig. 1 is a side view of an illustrative embodiment of the invention; and

Fig. 2 is a section on an enlarged scale along the line 2—2 of Fig. 1.

In the drawing, reference character 1 indicates a supporting rod which may be made of wood or other rigid material. Cones 2 and 3 of rigid insulating material are mounted upon the rod 1 at their small ends, and may be additionally supported at their large ends. Each cone 2, 3 is coated on the inside or outside, or both, with thin conducting layers 2' and 3' such as tin foil, aluminum foil or thin copper plating, for example. The conducting material is bonded at the small end thereof to metal rings 4 and 5, respectively, which fit tightly enough on the rod 1 to be held securely in position. Leads 6 and 7 extend from the rings 4 and 5, respectively, to the television receiver, not shown.

This antenna may be supported at both ends of rod 1 in any convenient way such as by placing the ends of rod 1 upon supports or suspending the same with cords or the like. Or it may be supported by a mast at the middle. It may be easily moved about and placed in an attic or storage room of a home where it is out of the way. A transmission line is then connected from it to the television receiver.

2

Heretofore antennas of this shape were made of solid cones or cones of sheet metal which made them very heavy or cumbersome. Such antennas are unsatisfactory because of the difficulty in moving them to the desired location or adjusting them to different positions for receiving television signals from different directions.

By the present invention the proper shapes and sizes of such antennas are made available while retaining the efficiency thereof. Since high frequency currents travel near the surface of conductors due to "skin" effect the conductor may be a thin metallic coating without loss in efficiency.

15 15. What is claimed is:

1. A television antenna comprising a single integral central supporting rod of rigid material, cones of rigid insulating material each less than half the length of said rod supported on an intermediate portion of said rod at their small ends with a short space between said small ends, thin layers of conducting material coating said cones, and cylindrical metal rings on said rod at the small ends of said cones on the outside of said rod bonded to said conducting material for making connection to a receiver.

2. The antenna of claim 1 in which said conducting material is applied to both the inside and outside surface of said cones.

3. The antenna of claim 1 in which the ends of said rod extends beyond the outer ends of said cones.
